TRAFFIC RAMP

Richard R. Bywater, St. Louis, Mo.

Application July 9, 1934, Serial No. 734,370

1 Claim. (Cl. 104—124)

This invention relates to traffic ramps, and its general object is to provide a ramp that is primarily designed for use across the intersections of streets, to expedite vehicle and pedestrian traffic and to prevent accidents.

A further object of the invention is to provide a traffic ramp that includes channel runways, having concaved serrated tread rails to provide positive purchase of vehicle tires therewith, and together with the channel structure guides the wheels with the result the ramp can be used by inexperienced drivers, with very little effort, as the possibility of running over the sides is eliminated.

Another object of the invention is to provide a traffic ramp having channel runways that are amply supported and reinforced to prevent displacement and the like regardless of the type of vehicle using the same and whether or not it is equipped with single or dual wheels.

Another object of the invention is to provide a traffic ramp that takes up minimum space, is of an open type construction and allows for the passage of ample light therethrough.

A still further object of the invention is to provide a traffic ramp of the character set forth, that is simple in construction, inexpensive to erect, and is extremely efficient in use and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a top plan view of a ramp constructed in accordance with the present invention, and shows the same at an intersection.

Figure 2 is a fragmentary enlarged view illustrating portions of the runways and the anchoring means therefor.

Figure 3 is a vertical sectional view taken through a portion of the ramp with parts in elevation.

Figure 4 is an enlarged sectional view taken through one of the runways.

While, in the following description I shall make reference to a number of parallel and spaced vehicle pathways, it is to be understood that the same is merely to disclose my device arranged to accommodate vehicles which have their wheels

differently spaced and that such arrangement forms no part of my present invention.

Referring to the drawings in detail, and particularly to Figure 1, it will be noted that I have illustrated a dual traffic ramp for use by double lanes of traffic going in opposite directions, with ramps disposed upon opposite sides of a street and across the intersection, but a single ramp would be erected across the intersection and longitudinally of the center of the street, as will be apparent. Each ramp includes an abutment or base means 1, at the opposite ends thereof within which is embedded the anchoring means for the runways which together with the anchoring means will be presently described, and the runways are broadly indicated by the reference numeral 2, while the side walks for pedestrian traffic are numbered 3.

It will be obvious that the ramps have the runways and side walks supported in arched formation and extend a considerable distance beyond the intersection as shown in Figure 1. The supporting means is in the form of columns 4 that are preferably constructed of I-beams having base means 5 provided with anchoring means 6 and bridging the columns 4 are cross ties 7 which are secured to the upper ends thereof by a suitable securing means including angle brackets 8, with reinforcing arms 9 having one of their ends fixed to the columns and their opposite ends to the cross ties as clearly shown in Figure 3.

The particular structure of the runways or stringers of my ramp is of extreme importance in that they provide maximum safety, and displacement and the like thereof, is practically impossible.

The runways or stringers each include foundation means that is provided with a pair of I-beams 10 that have their base portions fixed to the cross ties but spaced therefrom by plates 11, and arranged at intervals between the pair of I-beams of a runway are web plates 12 which hold the same in true parallel relation with respect to each other throughout the entire length thereof, and these plates are secured to the webs of the I-beams through the instrumentality of angle strips 13 which are fixed to the web plates and the webs of the I-beams respectively as clearly shown in Figure 4.

Resting upon the heads of each pair of I-beams are stringer plates 14 which are fixed to the heads and bridge the same as well as extend beyond the outer side edges thereof, and the stringer plates have fixed thereto angle members 15 having vertical portions which provide the sides for

the channel portions of the runways. Secured to the stringer plates through the medium of rivets or the like that extend along the longitudinal center thereof, are the tread means of my runway and which as best shown in Figure 4 include 5 transversely curved or concaved plate members 16 that have their side edges welded to the vertical portions of the angle members as at 17, to not only hold the vertical portions in true parallel relation with respect to each other but also to 10 provide a water tight connection, and the plate members 16 have disposed between the same and the horizontal portions of the angle members filler bars 18, so that the tread means will retain their concaved configuration regardless of the weight 15 of the traffic, as will be apparent. The plate members 16 are serrated upon the upper surface thereof throughout their length so that tires of vehicles will have positive purchase thereon, which of course prevents slippage and skidding. 20 The serrated tread plates 16, being of metal, have an inherent resiliency, and therefore are, to a determined extent, yieldable between their welded edges and the centrally and longitudinally arranged supporting filler or spacer bars 18. Vehicles 25 having their tires, traveling on parts of the tread plates, at points opposite the longitudinal center thereof, will thus naturally travel over a frictional, but yieldable surface and will be naturally held in proper position, that is in a straight 30 path which will obviate the liability of side movement or shifting thereof.

The runways are not only positively anchored in the abutments or base members 1, but the anchoring means connect the runways together 35 as clearly shown in Figure 2. The intermediate anchoring means each include a pair of converging arms 19 which have their remote ends fixed to the confronting sides of the runways and preferably to the vertical portions of the angle members 15, and the arms of the converging pairs curved toward each other, with their adjacent ends fixed together, as well as provided with anchoring strips 20 extending beyond the opposite 40 sides thereof as clearly shown in Figure 2. The pairs of arms have likewise bridging the same reinforcing members 21. The end anchoring means are in the form of strips 22 that are outwardly curved and have anchoring members 23 45 fixed to the outer sides thereof.

The I-beams 10 are likewise anchored as at 24 in the abutments or base members 1 and this an-

chorings means is preferably a continuation of the webs which have their ends bent in opposed directions with respect to each other as shown.

The arms 19 and strips 22 not only provide anchoring means for the runways but likewise guiding means, in that portions thereof are exposed and thereby direct the wheels of the vehicles to the runways as will be apparent upon inspection of Figures 1 and 2.

From the above description and disclosure of the drawings, it will be obvious that I have provided a traffic ramp that is not only completely safe for motor vehicle traffic, regardless of the type of vehicles, and whether or not they are equipped with single or dual wheels, but the open work construction allows for the passage of ample light to the street below, and the space between the runways may be covered by glass or other suitable transparent material.

The special construction of the runways is particularly adapted for vehicles having dual wheels, as it will be noted from Figure 4 that an I-beam will be disposed below each wheel, so that the weight will be equally distributed to the I-beams, therefore the runways are capable of supporting maximum weight with minimum vibration, and this is especially true due to the fact that the web plates 12 have a tendency to distribute the weight equally on each beam.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A traffic ramp comprising spaced parallel runways for the wheels of a vehicle and supports for 40 said runways, each runway comprising a base plate which extends longitudinally of the ramp, angle plates secured thereto, longitudinally extended bars resting on and secured to the base plate and likewise secured to the horizontal flanges of the angle plates, and a longitudinally extending upwardly concaved tread plate arranged transversely in the runway and having its edges welded to the vertical flanges of the angle plates, resting on the bars, and centrally secured 45 to the base plate.

RICHARD R. BYWATER.
